ROTARY SNOW PLOW

Bert R. Watkins, Austin, Minn.

Application March 28, 1938, Serial No. 198,518

18 Claims. (Cl. 37—43)

This invention relates to snow plows of the rotary type especially adapted for clearing roads or highways from snow and operable by and in advance of trucks, tractors or similar devices, and has for the primary object the provision of a device of this character which will rapidly and efficiently remove snow when frozen or non-frozen and also ice formations from a road leaving the latter substantially clear for use by ordinary vehicle traffic, the device including grouped rotary cutters and a laterally arranged rotary cutter cooperating therewith to cut snow and gather the latter to a pneumatic discharge apparatus which exhausts said snow well beyond a side shoulder or gutter of the road and thereby eliminates banking of snow on the shoulder or in the gutter of the road to act as a medium for bringing about drifting of the snow of the next storm on the road, a situation frequently brought about through the use of snow plows of the conventional construction.

With these and other objects in view, this invention consists in certain novel features of construction, combination and arrangement of parts to be hereinafter more fully described and claimed.

For a complete understanding of my invention, reference is to be had to the following description and accompanying drawings, in which:

30 Figure 1 is a side elevation partly in section illustrating a snow plow constructed in accordance with the present invention and showing the same adapted to a motor truck, only a fragmentary portion of the latter being disclosed.

35 Figure 2 is a front elevation illustrating the snow plow.

Figure 3 is a top plan view, partly in section, illustrating the device.

40 Figure 4 is a vertical sectional view showing the rotary cutters and the laterally arranged rotary cutter as well as the suction fan.

Figure 5 is a fragmentary horizontal sectional view showing the connection of the laterally arranged cutter on the housing of the rotary cutters.

Referring in detail to the drawings, the numeral 1 indicates a supporting frame to be mounted on the front end of a motor truck 2, as shown in Figure 1. A housing 3 is slidably and pivotally mounted in elongated slots provided in the supporting frame 1 and has a limited sliding movement on said frame. The housing 3 besides being supported by the frame 1 is also supported by ground skids 4. The housing 3 is of a shape 55 to present a comparatively large mouth 5 in the

front thereof and located along the upper and lower edges of said mouth are relatively spaced teeth 6 for biting into snow, ice and the like. The shape of the housing 3 also presents a fan chamber 7 in the rear portion of the housing to 5 which is connected an exhaust pipe 8, the discharge end of which is laterally disposed of the housing. A suction fan 9 operates in the fan chamber, the shaft of which is indicated by the character 10 and is shown as being journaled in the rear wall of the housing. The blades of the fan have pitches which act to draw snow within the housing 3 entering the latter by way of the mouth into the fan chamber and to expel the snow through the exhaust pipe 8. The shaft 10 15 is connected to a power shaft 11 by sprocket gears and a sprocket chain indicated generally by the character 12. The power shaft may be connected to a power source carried by the truck 2 or may be driven by the engine of the truck through a 20 suitable power takeoff. While this device has been described as being mounted on a truck and shown that way in Figure 1, it is to be understood that its application to a tractor or similar device can be easily had. Rotatably supported 25 by the housing 3 adjacent the mouth 5 thereof is a plurality of relatively spaced shafts 13 on which are mounted rotary cutters 14 each including radially extending blades having toothed ends adapted to bite into snow or ice for cutting the 30 same during the rotation of said shafts and to feed the snow and ice into the housing 3 wherein the fan acts on the snow and ice to expel the same through the exhaust pipe 8. During the rotation of the shafts 13 the blades move out- 35 wardly of the housing. The lower teeth 6 of the mouth move along the surface of the roadway while the uppermost teeth 6 are adapted to enter and bite into snow of considerable depth. The teeth 6 are disposed at an inclination so that 40 during the forward movement of the plow they tend to direct snow into engagement with the blades of the rotary cutters and they in turn cut the snow and feed the same into the housing 3. Sprocket gears 15 are secured to the shafts 45 13 of the rotary cutters and are connected by an endless sprocket chain 16 in such way that the rotary cutters adjacent to one another rotate in opposite directions. The sprocket chain 16 is trained over a sprocket gear 18 secured on a 50 shaft 19, the latter being journaled on the hangers 19' carried by the housing 3 and connected to the power shaft through the use of a worm and worm gear 20 and 21, respectively. The sprocket chain 16 is also trained over an idler sprocket 55

gear 22 adjustably mounted on the housing 3 whereby slack may be removed from the sprocket chain 16.

The shaft 19 is adjustable on the hangers 18' to permit slack to be removed from the sprocket chain.

One side of the housing 3 has a comparatively large opening 24 covered by a plate 25 slidably mounted on said housing, as shown at 26. The plate 25 has formed thereon a neck 27 always in communication with the opening 24 regardless of the adjusted positions of the plate 25 on the housing 3 and movably mounted in the neck is one end of a tubular housing 28 provided with a mouth 29 in the front thereof. Located along one edge of the mouth 29 are spaced teeth 30. A rotatable spiral cutter 31 is journaled in the tubular housing 28, the edges of the spirals being toothed, as shown at 32. The rotatable spiral cutter projects slightly outwardly of the mouth 29 and acts to cut snow, gather the same and feed the snow into the housing 3 by way of the neck 27 and opening in the side of said housing so that the snow will be discharged in the housing between the rotary cutters and the suction fan. Said suction fan gathers the snow and discharges the same through the exhaust pipe 8. The shaft of the spiral cutter has a sprocket gear 33 secured thereto and is connected to a sprocket gear 34 by a sprocket chain 35. The elongated slots provided in the supporting frame 1 will permit the snow plow to be longitudinally adjusted thereon, thereby permitting all slack to be removed from the sprocket chains 16 and 41 and to assure the efficient operation of the device at all times. The sprocket gear 34 is secured on a shaft 36 including in its construction universal joints 37 and a slip joint 38. The shaft 36 is supported by the tubular housing and a part of the frame 1 and has secured thereto a sprocket gear 39 connected to a sprocket gear 40 on the shaft 19 by a sprocket chain 41. Thus it will be seen that the rotary cutters at the mouth of the housing 3 and the spiral cutter in the tubular housing 28 are driven from the power shaft 11.

Levers 42 are pivotally mounted on the frame 1 and are connected to the housing 3 by links 43. The levers 42 engage with jacks 44 mounted on the frame 1 and of any desired construction preferably of the hydraulic type so that through the operation of said jacks the housing 3 may be tilted upwardly and downwardly of the frame 1.

A sub-frame 45 is carried by the frame 1 and supports a jack 46 similar to the jacks 44. The jack 46 is connected to a lever 47 pivoted on the sub-frame, as shown at 48. A flexible connection 49 is provided between the lever 47 and the neck 27 of the plate 25 so that through operation of the jack 46 the plate 25 may be moved upwardly and downwardly on the housing 3 to vary the tubular housing 28 with respect to the ground. Mounted on the housing 3 is an arm 50 carrying a jack 51 similar to the heretofore described jack. A lever 52 is secured to the tubular housing adjacent its free end and is pivotally and slidably connected to the jack 51 and has a pivotal and slidable connection with the arm 50, as shown at 53. Through the operation of the jack 51 the inclination of the tubular housing may be varied. The controls for the jacks may be of any desired character and form no part of the present invention as well as the detail construction of the jacks.

The purpose of the rotary spiral cutter is for the purpose of cutting and gathering snow on the shoulder or side of a road and feeding said snow

into the housing 3 to be discharged a desired distance from the road by the fan and the exhaust pipe. The snow in the road is cut and gathered by the rotary cutters operating adjacent the mouth 5 of the housing 3. The use of the rotary spiral cutter may at any time be done away with through the removal of the plate 25 and the disconnection of the rotary spiral cutter from the driving mechanism. The opening 24 in the housing 3 is then closed by a solid plate (not shown).

The housing 28 carries a bracket 28' to which is adjustably secured a brace 29' for aiding in sustaining the housing 28 in proper relation to the housing 3 during the use of the device.

What is claimed is:

1. A snow plow comprising a housing having a mouth in the front of said housing, a suction fan located in the rear portion of the housing, an exhaust pipe for said fan carried by the housing and extending laterally thereof, rotary cutters mounted for operation in the housing adjacent the mouth, a rotary cutter slidably and pivotally mounted on the said housing laterally of the said first-mentioned cutters for cutting and feeding snow into said housing and means for driving said cutters and the fan.

2. A snow plow comprising a housing having a mouth in the front of said housing, a suction fan located in the rear portion of the housing, an exhaust pipe for said fan carried by the housing and extending laterally thereof, rotary cutters mounted for operation in the housing adjacent the mouth, a rotary cutter slidably and pivotally mounted on the housing laterally of the said first-mentioned cutters, and a driving mechanism for the fan and the rotary cutters and rotating the said first-mentioned cutters in opposite directions to one another.

3. A snow plow comprising a housing having a mouth in the front of said housing, a suction fan located in the rear portion of the housing, an exhaust pipe for said fan carried by the housing and extending laterally thereof, rotary cutters mounted for operation in the housing adjacent the mouth, a driving mechanism including sprocket chains for the fan and the rotary cutters and rotating the cutters in opposite directions to one another, teeth at the upper and lower edges of the mouth and secured on said housing, ground skids for supporting the forward portion of the housing, a supporting frame having the housing pivotally and slidably mounted thereon forming an adjustable means assuring an efficient coaction between the drive and driven parts means for imparting pivotal movement to said housing for varying its mouth with the respect to the ground, and a rotatable wing auger slidably and pivotally mounted on the said housing and projecting laterally therefrom to direct snow banked at the side thereof into the said housing.

4. A snow plow comprising a housing having a mouth in the front of said housing, a suction fan located in the rear portion of the housing, an exhaust pipe for said fan carried by the housing and extending laterally thereof, rotary cutters mounted for operation in the housing adjacent the mouth, a driving mechanism for the fan and the rotary cutters and rotating the cutters in opposite directions to one another, teeth at the upper and lower edges of the mouth and secured on said housing, ground skids for supporting the forward portion of the housing, a supporting frame having the housing pivotally and slidably mounted thereon and adapted for mounting on a motor vehicle, means for imparting pivotal

movement to said housing for varying its mouth with respect to the ground, and a spiral type rotary cutter pivotally and slidably mounted on said housing and extending laterally therefrom 5 for cutting and feeding snow into said housing.

5. A snow plow comprising a housing having a mouth in the front of said housing, a suction fan located in the rear portion of the housing, an exhaust pipe for said fan carried by the housing 10 and extending laterally thereof, rotary cutters mounted for operation in the housing adjacent the mouth, a driving mechanism for the fan and the rotary cutters and rotating the cutters in opposite directions to one another, teeth at the upper and lower edges of the mouth and secured on 15 said housing, ground skids for supporting the forward portion of the housing, a supporting frame having the housing pivotally and slidably mounted thereon and adapted for mounting on a motor 20 vehicle, means for imparting pivotal movement to said housing for varying its mouth with respect to the ground, a tubular housing slidably and pivotally mounted on one side of said first housing and in communication with the latter 25 and having a mouth extending substantially the full length thereof, a toothed rotatable spiral cutter operating in the tubular housing for cutting and feeding snow into the first-named housing, and means for connecting said spiral cutter to 30 said drive mechanism.

6. A snow plow comprising a housing having a mouth in the front of said housing, a suction fan located in the rear portion of the housing, an exhaust pipe for said fan carried by the housing 35 and extending laterally thereof, rotary cutters mounted for operation in the housing adjacent the mouth, a driving mechanism for the fan and the rotary cutters and rotating the cutters in opposite directions to one another, teeth at the upper and lower edges of the mouth and secured on 40 said housing, ground skids for supporting the forward portion of the housing, a supporting frame having the housing pivotally and slidably mounted thereon and adapted for mounting on a motor vehicle, means for imparting pivotal movement to said housing for varying its mouth with respect to the ground, a tubular housing slidably and pivotally mounted on one side of said first housing and in communication with the latter 45 and having a mouth extending substantially the full length thereof, a toothed rotatable spiral cutter operating in the tubular housing for cutting and feeding snow into the first-named housing, means for connecting said spiral cutter to 50 said drive mechanism, means for raising and lowering the tubular housing on the first named housing and with respect to the ground, and means for varying the inclinations of the tubular housing on the first named housing.

60. 7. A snow plow comprising a housing having a mouth in the front thereof, a suction fan located in the rear portion of the housing, exhaust means for the said fan, rotary cutters mounted in the housing adjacent the mouth, a tubular housing slidably and pivotally mounted on one side of said housing and communicating therewith, a toothed rotatable spiral cutter in the tubular housing for cutting and feeding snow into the first-named housing, and means for driving the cutters and the said fan.

70. 8. A snow plow comprising a housing having a mouth in the front, and an opening in the side thereof, a suction fan located in the rear portion of the housing, exhaust means for the said fan, rotary cutters journaled in the housing adjacent 75

the mouth, a wing auger slidably and pivotally connected to the said housing adjacent the said opening to direct snow banked at the side thereof into the housing, and drive means for the said auger, cutters and fan.

9. A snow plow comprising a housing having a mouth in the front thereof, a suction fan located in the rear portion of the housing, exhaust means for the said fan, rotary cutters mounted in the housing adjacent the mouth, a drive mechanism 10 for the fan and the rotary cutters, and rotating the cutters in opposite directions to one another, teeth at the upper and lower edges of the mouth and secured on said housing, ground skids supporting the forward portion of the housing, a supporting frame having the housing pivotally and slidably mounted thereon and adapted to be supported on a motor vehicle, means for imparting pivotal movement to said housing for varying its mouth with respect to the ground, a tubular 20 housing slidably and pivotally mounted on one side of said first housing, in communication therewith, and having a mouth extending substantially the full length thereof, a toothed rotatable cutter in the tubular housing for cutting and feeding snow into the first-named housing, and means connecting the last mentioned cutter to 25 said drive mechanism.

10. A snow plow comprising a housing having a mouth in the front thereof, a suction fan located in a rear portion of the housing, exhaust means for said fan, rotary cutters mounted in the housing adjacent the mouth, a driving mechanism for the fan and the rotary cutters, and rotating the cutters in opposite directions to one another, ground skids supporting the forward portion of the housing, a supporting frame attached to a motor vehicle and having the housing pivotally and slidably mounted thereon, means for imparting pivotal movement to said housing 30 for varying its mouth with respect to the ground, a tubular housing slidably and pivotally mounted on one side of said first housing and in communication therewith, a toothed rotatable spiral cutter operating in the tubular housing for cutting and feeding snow into the first-named housing, and means connecting said spiral cutter to 35 said drive mechanism.

11. A snow plow comprising a housing having a mouth in the front thereof, a suction fan located in the rear portion of the housing, exhaust means for the said fan, rotary cutters mounted in the housing adjacent the mouth, a driving mechanism for the fan and the rotary cutters, and rotating the cutters in opposite direction to 40 one another, a supporting frame mounted on a motor vehicle and having the housing pivotally and slidably mounted thereto, means for imparting a vertical pivotal movement to said housing, a tubular housing slidably and pivotally mounted on one side of said first-mentioned housing and in communication therewith, a toothed rotatable spiral cutter operating in the tubular housing for cutting and feeding snow into the first-named housing, and means for connecting said spiral 45 cutter to said drive mechanism.

12. A snow plow comprising a housing having a mouth in the front thereof, a suction fan located in the rear portion of the housing, exhaust means for the said fan, rotary cutters journaled in the housing adjacent the mouth, a driving mechanism for the fan and the said cutters, a tubular housing slidably and pivotally mounted on one side of the said first housing and in communication therewith, a toothed rotatable 50

spiral cutter operating in the housing for cutting and feeding snow into the first-named housing, and means for connecting said spiral cutter to said drive mechanism.

5 13. A snow plow comprising a housing having a mouth in the front thereof, a suction fan located in the rear portion of the housing, exhaust means for the said fan, rotary cutters journalled in the housing adjacent the mouth, a drive 10 mechanism for the fan and said rotary cutters, a supporting frame carried by a motor vehicle and having the housing pivotally and slidably mounted thereon, means for imparting a vertical pivotal movement to said housing, a tubular 15 housing projecting laterally of the said first-mentioned housing and slidably and pivotally connected thereto, a rotatable cutter operating in the tubular housing for cutting and feeding snow into the first-named housing, and means to 20 rotate said last-mentioned cutter.

14. A snow plow comprising a housing having a mouth in the front thereof, rotary cutters journalled in the housing adjacent the mouth, and means to discharge the snow from the said 25 housing, a drive mechanism for the discharge means and said rotary cutters, a tubular housing slidably and pivotally mounted on one side of said first named housing and in communication therewith, a rotatable spiral cutter mounted in 30 the tubular housing for cutting and feeding snow into the first-named heusing, and means for connecting said spiral cutter to said drive mechanism

15. A snow plow comprising the combination 35 of a housing having a mouth in the front thereof, rotary cutters mounted in the housing adjacent the mouth, a rotatable cutter extending laterally of the said housing and having a slideable and pivotal connection therewith, means to 40 rotate the said cutters, and means to discharge the snow from the said housing.

16. A snow plow comprising a housing having a mouth in the front thereof, rotary cutters mounted in the housing adjacent the mouth, a supporting frame attached to a motor vehicle and having the housing pivotally and slidably mounted thereon, means for imparting a vertical pivotal movement to the housing, a tubular housing slidably and pivotally mounted on one side of said

first housing and in communication therewith, a toothed rotatable spiral cutter operating in the tubular housing for cutting and feeding snow into the first-named housing, a drive mechanism for the said cutters, means for raising and lowering the tubular housing, means for varying the inclinations of the tubular housing with respect to the said first-mentioned housing, and means to discharge the said snow from the said housing.

17. A snow plow comprising a housing having a mouth in the front thereof, a plurality of spaced rows of cutters extending horizontally across the mouth of the said housing and projecting forwardly thereof, a driving mechanism to rotate adjacent rows of cutters in opposite directions, a tubular housing slidably and pivotally mounted on one side of said first housing, in communication therewith, and having a mouth extending substantially the full length thereof, a toothed rotatable spiral cutter operating in the tubular 20 housing for cutting and feeding snow into the first-named housing, means for connecting said spiral cutter to said drive mechanism, means for raising and lowering the tubular housing on the first-mentioned housing, means for varying the 25 inclinations of the tubular housing on the first-named housing, and means to discharge the said snow from the said first-mentioned housing.

18. A snow plow comprising a housing having a mouth in the front thereof, a plurality of spaced 30 cutters extending across the mouth of the housing, a driving mechanism to rotate adjacent cutters in opposite directions to one another, a supporting frame attached to a motor vehicle and having the housing pivotally and slidably mounted thereto, means for imparting a vertical pivotal movement to the housing, a tubular housing slidably and pivotally mounted on one side of said first housing and in communication therewith, a toothed rotatable spiral cutter operating 35 in the tubular housing for cutting and feeding snow into the first-named housing, means for connecting said spiral cutter to said drive mechanism, means for raising and lowering the tubular housing on the first-named housing, means for varying the inclinations of the tubular housing on the first-named housing, and means to discharge the said snow from the housing.

BERT R. WATKINS.
